UNITED STATES PATENT OFFICE

WILLIAM F. KIESEL, JR., OF HOLLIDAYSBURG, PENNSYLVANIA

HOPPER CAR

Application filed September 25, 1930. Serial No. 484,258.

This invention relates to hopper cars or the like and has particular reference to the division of the car body into several compartments, each compartment leading to hoppers with drop doors for discharging the lading at the bottom of the car body. Hopper cars generally similar to the type hereinafter described are adapted to be unloaded in several different ways. For example, the 10 contents may be discharged through the bottom doors; the car may be bodily overturned by an upsetting device; or the contents may be scooped out by buckets or shovels. The object of the present invention is to provide 15 transverse partitions or gussets dividing the car body into separate compartments, the partitions being so designed and related to the surrounding parts as to form cross-bearers for rigidifying the body and at the 20 same time facilitating, or at least in no wise impeding, the discharge of the contents by any of the above methods.

Other objects and advantages characterizing my invention will be apparent from the 25 detailed description, which follows herein-after, of one embodiment or example of the invention as applied to a hopper car, having reference to the accompanying drawings, whereof:

30 Fig. I represents a top plan view of a section of a hopper car adjacent one set of twin-hoppers.

Fig. II represents a side elevation of the 35 same with a portion of the side wall cut away at one of the transverse partitions.

Fig. III represents a transverse section of the car at one of the transverse partitions taken as indicated by the lines III—III of Fig. I; and,

40 Fig. IV represents an enlarged cross-section taken at the center sill as indicated by the lines IV—IV of Fig. III.

With particular reference to Figs. I and 45 II there is shown a section of a hopper car, representative of succeeding sections, illustrating the manner in which the hoppers are formed throughout the car body. The side walls 1 are supported at intervals of their length by stakes 2 and are preferably 50 formed with their upper portions 3 inclined

upwardly toward the center of the car, the stakes 2 having extensions 4 on the outside of the side walls 1 terminating in top rails 5 in the form of Z-bars with their down-turned flanges 6 riveted to the side walls. 55 At their bottom edges the side walls 1 are turned inward at 7, as shown in Fig. III, and are riveted to bottom chords 8 of the side trusses in the form of relatively thick plates disposed at an angle of approximately 45 degrees with the side walls 1. 60

The hoppers comprise side sheets 9 with their upper edges inclined outward and upward and riveted to the bottom chords 8 and abutting the lower edges of the side walls 1, slope sheets 10 riveted to the side sheets, and hinged doors 11, the hoppers being arranged in pairs at both sides of the center sill 12. Between successive hopper compartments, there are two sets of cross-ridge sheets 13 and 22, the sheets 22 overlapping the sheets 13 and each set comprising sheets sloping downward in opposite directions to facilitate the discharge of the car contents. Additional inclined sheets 14 70 running longitudinally of the car slope off from the center sill 12 toward the hoppers and are riveted to the slope sheets 10. 75

The partitions between hopper compartments comprise a U-shaped gusset preferably formed of two triangular plates 15 disposed at the sides of the car and a central filler plate 16 fitting therebetween. The triangular gusset plates 15 are secured at their outer edges to opposite side stakes 2 in the form of angles which in turn are riveted to the side walls 1. A continuous reinforcing strip 17 anchored at its ends to the side stakes 2 extends from one side of the car to the other and covers the upper edges of the gusset, the strip 17 comprising a flat plate bent around the upper margins of the gusset plates to completely surround their top edges and curved with respect to its length to substantially a U-shape to conform with the sharply inclined top edges of the triangular plates 15 and the concaved top edge of the central filler plate 16. The filler plate 16 is cut away at the bottom to accommodate the center sill 12, the bottom edges 80 85 90 95 100

of the filler plate 16 partially surrounding the center sill 12 and being provided with an inverted U-shaped reinforcing strip 18 riveted to the center sill.

5 Extending across the car beneath the center sill 12 there are paired angles 19. At their outer ends the angles are turned upward and anchored to the bottom chords 8. The angles 19 hold riveted between their 10 opposed flanges 20 the bottom edges of the gusset plates 15 and 16. At the center of the car the angles 19 join the ends of the reinforcing strip 18 and pass under the center sill 12 to which they are riveted. The 15 cross ridge sheets 13 and 22 have opposed flanges 21 and 23 riveted to the gusset plates 15 and 16.

It will be evident that the gusset plates 15 and 16 serve not only as partitions between hopper compartments but as cross-bearers, the plates being protected and stiffened at their top edges by the U-shaped reinforcing strip 17, at the outer edges by the side stakes 2, and at their bottom edges 25 by the transverse angles 19 and the inverted U-shaped reinforcing strip 18. The provision of a U-shaped opening at the top of the partitions formed by the gusset plates permits the unloading of the major portion 30 of the car contents by buckets or scoops, the strength of the partition as a cross-bearer being nevertheless undiminished and the top edge of the same being amply reinforced by the continuous strip 17 extending the full 35 width of the car.

In the arrangement herein described, sharp angles, cavities or projections at which water, coal, dirt, or other matter likely to accelerate corrosion or deterioration, may 40 accumulate have been conspicuously avoided, and the hopper side sheets 9 and slope sheets 10 leading to the bottom doors 11 have been designed to facilitate the discharge of the load. At the bottom of the side walls 1, the 45 provision of bottom chords 8 in the form of flat plates inclined inwardly and downward toward the center of the car to which are riveted the abutting edges of the side walls 1 and hopper side sheets 9 results in 50 a gradually inward sloping side. At the partitions and at the center sills the cross-ridge sheets 13 and 22 and longitudinal sheets 14 are similarly sloped downward toward the hoppers.

55 While I have described my invention with reference to one embodiment thereof in a hopper car, it will be apparent, especially to those skilled in the art that various changes may be made in the form of the 60 apparatus disclosed without departing from the spirit of the invention as defined in the claims hereto annexed, and that certain features of the invention may at times be used to advantage without a corresponding use 65 of other features.

Having thus described my invention, I claim:—

1. In a freight car, a number of hoppers, a center sill running longitudinally through said hoppers, and a transverse partition between said hoppers, said partition comprising a gusset extending from one side of the car to the other and having a U-shaped opening at the top, and said partition serving as a cross-bearer to support the center 75 sill from the sides of the car.

2. In a freight car, a number of hoppers, a transverse gusset between said hoppers, said gusset comprising two triangular plates and a central filler plate forming therewith 80 a U-shaped partition extending from one side of the car to the other, and a reinforcing strip covering the upper edges of said plates.

3. In a freight car, a number of hoppers, a center sill running longitudinally between said hoppers and a cross-bearer forming a transverse partition between said hoppers, said cross-bearer comprising a transverse reinforcing member joining the sides of the car above said center sill, said upper reinforcing member being sharply inclined from its ends toward the center, and a flat plate 85 extending across the car between said upper and lower transverse members. 90

4. In a freight car, a number of hoppers, a center sill running longitudinally through said hoppers and a gusset forming a transverse partition between said hoppers, said gusset comprising a U-shaped reinforcing 100 strip extending from one side of the car to the other above the center sill, an inverted U-shaped reinforcing strip partially surrounding the center sill, a transverse reinforcing strip extending from one side of the 105 car to the other beneath said center sill, and flat plates bounded by the aforesaid reinforcing strips.

5. In a freight car, a number of hoppers, stakes at the side walls of the car, a transverse partition between said hoppers, said partition comprising a flat gusset extending from one side of the car to the other and having a U-shaped opening at the top, and a continuous reinforcing strip in the 110 form of a flat plate bent over the upper edge of said gusset and secured at its ends to opposite side stakes. 115

6. In a freight car, a number of hoppers, a center sill running longitudinally of said 120 hoppers, and a transverse partition between said hoppers, said transverse partition comprising two triangular plates disposed at the sides of the car and a central filler plate having an opening in the bottom thereof to accommodate the center sill, and having a top edge forming with said triangular plates a U-shaped opening extending from one side 125 of the car to the other.

7. In a freight car, a number of hoppers, 130

a center sill running longitudinally of said hoppers, and a transverse partition between said hoppers, said transverse partition comprising two triangular plates disposed at the sides of the car and a central filler plate having an opening in the bottom thereof to accommodate the center sill and having a concaved top edge, and a reinforcing strip covering the top edges of said plates and extending from one side of the car to the other.

8. In a freight car, a number of hoppers, a center sill running longitudinally through said hoppers, side trusses having bottom chords and side stakes secured thereto, and a cross-bearer between said hoppers, said cross-bearer including a U-shaped reinforcing strip extending from one side stake to another above the center sill, an additional reinforcing strip extending across the car beneath the center sill and joining said bottom chords, and a gusset filling the interspace between said reinforcing strips.

In testimony whereof, I have hereunto signed my name at Altoona, Pennsylvania, this 22nd day of September, 1930.

WILLIAM F. KIESEL, JR.
